UNITED STATES PATENT OFFICE.

WILLIAM H. VOSS, OF DAVENPORT, IOWA.

WRINGER MECHANISM.

Application filed June 28, 1921. Serial No. 440,624.

The present invention relates primarily to release mechanisms for wringer rolls. Among the objects of my invention are: to provide, in a wringer, mechanism whereby the tension on the wringer rolls may be easily and quickly released in the event clothing should get bunched or the fingers caught between the rolls, or if for any other reason it should be desirable to release the tension; to provide mechanism of the character described such that the tension on the rolls can be easily released without the fingers getting injured; to provide release mechanism of the character stated, which is easily reset to normal operating position after it has been released; to improve in general upon mechanisms of the character stated; and such further objects, advantages and capabilities as will later more fully appear.

My invention further resides in the combination, construction and arrangement of parts illustrated in the accompanying drawing, and while I have shown therein preferred embodiments I desire the same to be understood as illustrative only and not as limiting my invention.

In the drawing annexed hereto and forming a part hereof, Fig. 1 is a sectional elevation of a wringer embodying my improvements; Fig. 2 is a transverse section substantially along the plane indicated by the line 2-2 Fig. 1; and Fig. 3 is a fragmentary section of a modification of my release mechanism.

Referring more in detail to the drawing, numeral 1 denotes the upright side members of the wringer frame, 2 the wringer rolls and 3 the gear casings surrounding the gears and the ends of the rolls as is customary. Connecting the members 1 are cross bars or plates 4, provided centrally with hollow bosses 5, in the hollows 6 of which slide the trunnions 7 on block 8. The block 8 is provided as shown with a notch 9, adapted to engage an abutment member, such as a bolt 10 passing through and connecting the side plates 4, which are also connected by means of a plurality of bolts 11. Passing approximately centrally through block 8 is a screw threaded tension adjusting means 12 provided with a hand wheel 13. This rests at its lower end upon a spring 14 which serves to transmit tension to the rollers 2 so as to hold them yieldingly, as is customary. It will be seen from the above that when the parts are in the solid line position, shown

in Figs. 1 and 3, there will be a direct upward thrust of the spring 14 against the end of screw 12, which is transmitted thereby to the block 8, which is prevented from upward movement by the bolt 10 engaging in notch 9. When it is desired to release the tension on spring 14 and the rollers 2, it is only necessary to press downwardly on handle 15 connected with block 8 and notch 9 is moved out of engagement with bolt 10, thereby releasing block 8 for movement upwardly. When this happens trunnions 7 slide upwardly in the grooves 6 and so quickly release the pressure on the rolls. In order to reduce wear and render the device more easy of operation, bolt 10 is surrounded by a sleeve which is, in effect, a roller bearing, the trunnions 7 and tops of grooves 6 co-operating to permit bodily movement of block 8 but preventing same from becoming detached.

In the form shown in Fig. 3 it might be possible for one to get the fingers between the handle 15 and the side pieces 4 and thereby get hurt when the tension is released from the rollers. In the form shown in Fig. 1 this danger is obviated by placing a hinge 16 in the handle 15 so that when the handle is pressed downwardly the block 8 can be released from bolt 10 as described, but the further movement of this block under the influence of spring 14 cannot cause the end of handle 15 to pinch the fingers between the handle and the side plates 4.

It will be seen from the above that with my new construction it will be extremely simple to press the handle 15 downwardly as indicated and release the tension on the rolls 2 and that when so released the upper roll can move upwardly a considerable distance so that bunches of clothing going through the wringer rolls will not cause any damage. It is also clear that it is easy to return the parts to normal position after the clothing or other obstruction has been removed from the wringer. It is further clear that with the construction shown in Fig. 1 it will be impossible to get the hands hurt between the handle 15 and side pieces 4. Along with these advantages is the advantage of being able to have a uniform tension on the two ends of the rolls because of the fact that the tension is transmitted from the single adjusting means 12, 13, through the spring 14 to the rolls 2.

It is of course understood that the specific

description of structure set forth above may be departed from without departing from the spirit of my invention.

Having now described my invention I claim:

1. In a wringer, a pair of rolls, a spring for placing tension upon said rolls, said wringer having a pair of side members provided with approximately centrally arranged grooves, a block between said side members carrying a pair of trunnions, said trunnions being slidable in the grooves in the side plates, said block carrying tension adjusting means adapted to engage the spring and transmit tension therethrough to the wringer rolls, said block being provided with a notch and said plates being connected by a bolt adapted to engage in said notch to hold the block in normal position, and a handle for tilting said block on its trunnions to release the notch from the bolt, thereby releasing the tension on the wringer rolls.
2. In a wringer having a pair of spaced side members and a roll tensioning spring, means extending transversely between and connected to said side members and adapted to serve as an abutment for a movable member, a movable member in engagement with said spring, side members and abutment means adapted to hold the spring under tension, and means for moving the spring holding means out of engagement with the abutment so that it may move bodily away from the rolls to permit quick release of the tension on the spring.
3. In a wringer, a frame having an opening and having an abutment within its opening, a block pivotally mounted within said opening and capable of sliding movement therein in a direction transverse to the pivotal axis, said block being adapted in one position thereof to engage said abutment so as to be prevented from sliding movement and, further, being adapted to be readily moved pivotally to be released from said abutment.
4. In a wringer, a frame having an opening and having an abutment within its opening, a block pivotally mounted within said opening and capable of sliding movement therein in a direction transverse to the pivotal axis, said block being adapted in one position thereof to engage said abutment so

as to be prevented from sliding movement and, further, being adapted to be readily moved pivotally to be released from said abutment, and means rigid with said block for manually moving said block on its pivots.

5. In a wringer, a frame having an opening and having an abutment within its opening, a block pivotally mounted within said opening and capable of sliding movement therein, said block being adapted in one position thereof to engage said abutment so as to be prevented from sliding movement and, further, being adapted to be readily moved pivotally to be released from said abutment, and a handle comprising sections jointed together to break upwardly when the handle is moved toward the frame when manually releasing said block from the abutment.

6. In a wringer comprising a frame carrying rolls and compressing means therefor, the combination of means for varying the compression of the rolls, means normally holding the varying means in compressing position, and a handle formed of jointed sections adapted to break upwardly when moved towards the frame to release the varying means.

7. In a wringer, a frame having an opening and having an abutment and guideways within its opening, a block mounted within said opening on pivots capable of sliding movement in said guideways, said block having means adapted, in one position thereof, to engage said abutment so as to be prevented from sliding movement and, further, being adapted to be readily moved pivotally to be released from said abutment, said abutment comprising a rotatably mounted sleeve.

8. In a wringer having a frame comprising side members so positioned as to form an open top, an abutment within said top comprising a rotatably mounted sleeve, supported by the side members, a movable member in said top adapted to rest against said abutment and to be detached therefrom, means permitting said member to move bodily and pivotally but preventing same from becoming detached from the top.

In witness whereof, I hereunto subscribe my name to this specification.

WILLIAM H. VOSS.

Certificate of Correction.

It is hereby certified that in Letters Patent No. 1,601,894, granted October 5, 1926, upon the application of William H. Voss, of Davenport, Iowa, for an improvement in "Wringer Mechanism," errors appear in the printed specification requiring correction as follows: Page 1, line 70, after the word "rolls" strike out the period and insert a comma and the words *the trunnions 7 and tops of grooves 6 cooperating to permit bodily movement of block 8 but preventing same from becoming detached*; same page, lines 74 to 77, strike out the comma and words "the trunnions 7 and tops of grooves 6 cooperating to permit bodily movement of block 8 but preventing same from becoming detached"; and that the said Letters Patent should be read with these corrections therein that the same may conform to the record of the case in the Patent Office.

Signed and sealed this 21st day of December, A. D. 1926.

[SEAL.]

M. J. MOORE,
Acting Commissioner of Patents.
